PRODUCTION OF HYDROCARBON FUELS

William E. Bradley, Los Angeles, Calif., assignor
to Union Oil Company of California, Los Angeles, Calif., a corporation of California

No Drawing. Application March 19, 1940,
Serial No. 324,806

5 Claims. (CL. 260—688.4)

This invention relates to a process for manufacturing hydrocarbon motor fuel and more specifically pertains to the production of hydrocarbon fuels of an isoparaffinic character particularly suitable for use in automobile and aviation engines. The present specification is a continuation in part of my co-pending application Serial No. 202,723 filed April 18, 1938.

It is the main object of this invention to provide a simple method for producing, by physical treatment of raw materials and subsequent controlled chemical reactions thereof, a gasoline of improved volatility characteristics and anti-knock rating.

Owing to the adoption of high compression ratios in automobile and aviation gasoline engines, an insistent demand has been made upon petroleum refiners and similar industries to furnish motor fuels which have high anti-knock values. Thus, in the aviation industry many specifications require a gasoline having an anti-knock rating of about 100 iso-octane (as determined by the A. S. T. M. method) and containing not more than 3 milliliters of tetraethyl lead per gallon of such gasoline. This demand for fuels of unusually high anti-knock quality is due primarily to the high payload efficiency which may be realized in commercial aviation and to certain definite tactical advantages to be gained in military aviation when motor fuels of this type are employed.

The use of knock inhibitors, for example, tetraethyl lead, aniline, iron carbonyl, nickel carbonyl, etc., are effective in various degrees in increasing the anti-knock rating of gasolines but the use of these compounds is limited due to certain inherent disadvantages, such as toxic effects and tendencies to crystallize out at low temperatures, to form sludge, to corrode engine parts, etc. Olefin and aromatic hydrocarbons are known to possess high anti-knock values but it has been considered advisable to limit the percentages of such compounds which may be present in gasolines, at least in the case of aviation fuels, to negligible amounts.

The foregoing limitations therefore make it essential to produce fuels consisting primarily of stable hydrocarbons of inherently high anti-knock value. It is now well recognized that such hydrocarbons comprise the branched-chain

paraffinic hydrocarbons, the normal or straight chain hydrocarbons boiling above normal pentane being of comparatively low anti-knock value.

Automobile and aviation fuels, particularly the latter, are comprised to a large extent of hydrocarbons having 7, 8 and 9 carbon atoms, and may contain also hydrocarbons having as high as 12 carbon atoms. A minor proportion of the gasoline is comprised of hydrocarbons having 5 and 6 carbon atoms, but this portion is essential and its properties are of importance because of their direct influence on the starting characteristics of the gasoline.

Previously, as disclosed in my co-pending application, I have discovered that branched-chain hydrocarbons containing 7, 8 and 9 carbon atoms can be readily formed by an alkylation process comprising reacting propylene, butylenes and pentenes with iso-butane in the presence of concentrated sulfuric acid. Due to side reactions, some branched-chain hydrocarbons containing 6 and 10 or more carbon atoms are also formed but the product, although of especially high anti-knock rating does not possess the proper volatility characteristics, as indicated by the Engler distillation, to make it a desirable fuel for present type internal combustion engines. In preparing an acceptable gasoline from such an alkylation product it has normally been necessary to produce a special, light fraction of straight-run gasoline from selected crude oils and subsequently to blend this material with the gasoline obtained from the alkylation process. In order to produce the aforementioned special gasoline fraction a separate fractional distillation unit has been required and the blending operation has necessitated other extra equipment. Furthermore, since the anti-knock rating of even the best straight-run gasolines is not more than about 70, and usually lower, such blending results in the production of a gasoline of balanced distillation characteristics but lowered anti-knock rating and requiring the addition of a knock inhibitor, such as tetraethyl lead, in order to give a material having the same anti-knock rating as the original alkylation product.

Further, in my co-pending application mentioned hereinabove, it is noted that isopentane likewise will react with olefins to produce higher-boiling branched-chain paraffin hydrocarbons

but at a somewhat slower rate than isobutane. On the other hand, normal paraffin hydrocarbons and naphthenes do not appear to react appreciably with olefins when sulfuric acid is employed as the catalyst.

I have now discovered that in producing a gasoline by the alkylation process, a material of the desired volatility can be directly prepared, without the necessity for extra equipment, by employing olefin and isoparaffin fractions that contain a quantity of relatively unreactive hydrocarbons having 5 and 6 and under some circumstances possibly more carbon atoms. I have further discovered that by reacting a mixture of isopentane and isobutane with olefins, particularly the normally gaseous olefins, and subsequent fractionation, I can take advantage of their above noted difference in reaction rates and produce in a single operation a gasoline of improved distillation and volatility characteristics and comprised substantially of all branched-chain paraffinic hydrocarbons, said gasoline having an anti-knock rating equivalent to that of the usual alkylation gasoline produced by reacting the same olefins with isobutane alone. Furthermore, by regulating the proportions of isobutane, isopentane and olefins, I can obtain additional control of the character of the alkylation product; in general, by maintaining a high molal ratio of isobutane to isopentane and a high molal ratio of isobutane plus isopentane to olefin in the reaction mixture, the reacting olefins will combine primarily with isobutane and only to a minor extent with isopentane, with the result that the product obtained after stabilization to remove materials boiling below isopentane will contain an appreciable quantity of the latter material.

It is thus an object of the present invention to produce directly, by proper selection of reacting stocks and subsequent treatment, a gasoline of high anti-knock rating and improved volatility characteristics. It is a further object of the invention to produce a gasoline comprised essentially of branched-chain hydrocarbons and requiring the addition of no, or only a minimum of, straight-run gasoline in order to yield a product of desired volatility and Engler distillation characteristics. It is another object to produce a gasoline comprised substantially of branched-chain hydrocarbons and having a relatively high vapor pressure, said gasoline being formed by reacting a mixture of isobutane and isopentane with olefins under such conditions that only a part of the isopentane is alkylated and subsequently fractionated to remove hydrocarbons boiling below isopentane.

Briefly, where it is desired to produce directly a gasoline of improved volatility and comprised essentially of only branched-chain hydrocarbons, my preferred process may be described as follows:

An isoparaffin fraction comprised of isobutane and isopentane is obtained by distillation or other means from a suitable stock, such as for example natural gasoline. This fraction will usually contain normal butane also and possibly propane but must be sufficiently closely fractionated so as not to contain any appreciable percentage of normal pentane for reasons which will be apparent hereinafter. The molal ratio of isobutane to isopentane may vary over a considerable range, depending upon the percentage of isopentane desired in the final product and the molal ratio of isobutane plus isopentane to reacting olefins, but the ratio should be preferably not less than 1 to 1 and it is desirable that it should be of the order

of 10 to 1 or it may even be as high as 95-100 to 1. For example, suppose 95 mols of isobutane and 5 mols of isopentane were reacted with 10 mols of isobutylene. After stabilization to remove materials boiling below isopentane, the resultant product would contain 10 mols of higher boiling branched-chain hydrocarbons and approximately 5 mols of isopentane. Actually the amount of isopentane present would be slightly less due to reaction of a small proportion of the isopentane with isobutylene. It can be seen that by decreasing the molal ratio of isobutane plus isopentane to isobutylene or decreasing the ratio of isobutane to isopentane, maintaining the molal ratio of isobutane plus isopentane to olefin constant, the proportion of isopentane in the stabilized product can be readily decreased to any desired extent.

The olefin-containing fraction to be reacted with the isoparaffin fraction may be comprised of various olefins as indicated in my previous application but for the purpose of the present example this fraction must contain substantially no cyclic or straight-chain paraffin hydrocarbons boiling above isopentane. A typical olefin-containing fraction suitable for the purposes of the present invention would be the gases derived from the stabilization of pressure distillate. Such a material is normally comprised of hydrocarbons boiling below isopentane and may contain as much as 50% of propylenes and butylenes. If it is desired, however, the olefin fraction may contain pentenes and isopentane but fractionation must be sufficiently good so that the material contains little or no normal pentane or higher boiling paraffinic and cyclic hydrocarbons. If there is an appreciable proportion of isopentane present in the olefin-containing fraction then the isobutane-isopentane mixture with which it is to be reacted may contain a correspondingly smaller proportion of isopentane and may even contain no isopentane, it only being necessary that the mixture of olefin and isoparaffin fractions coming into contact with the catalyst in the reaction zone contain isobutane, isopentane and olefins in the desired proportions.

Normally, in order to prevent polymerization of the olefins by the alkylation catalyst, it is desirable to maintain an excess of isoparaffins over that required to react with the olefins in the reaction zone. For the purposes of the present invention the number of mols of isobutane plus the number of mols of isopentane should be at least three to five times as great as the number of mols of olefins present in the reaction zone and preferably even higher. In conducting the alkylation reaction the olefin-containing fraction and the isobutane-isopentane fraction are brought together in the presence of an alkylation catalyst such as, for example, concentrated sulfuric acid, the reactants being introduced into the contacting zone at rates sufficient to maintain the above desired molal proportions of reacting isoparaffins to olefins. After sufficient time has been allowed for the reaction to complete itself, the catalyst is separated from the hydrocarbon product and the latter fractionated to remove materials boiling below isopentane. The residual material may be further fractionated, if desired, in order to remove high boiling alkylation products. For example, in producing gasoline for use in aviation engines, those hydrocarbons boiling above about 320° F. are usually removed by distillation. The resultant aviation gasoline will be comprised wholly of

branched-chain paraffinic hydrocarbons and will contain a substantial portion of isopentane.

It is immediately evident from a consideration of the above description of my preferred process and the boiling points of isopentane and normal pentane that if any appreciable proportion of the latter, or other higher boiling hydrocarbons of low anti-knock rating, was present in the stocks introduced into the reaction zone, it would be present in the finished gasoline and as a consequence would lower the anti-knock rating of the product.

In the foregoing discussion concentrated sulfuric acid has been used as illustrative of an alkylation catalyst, but for the purposes of the present invention, it is evident that any other type of alkylation catalyst, such as for example, aluminum chloride, boron trifluoride, etc., could likewise be used with equal facility without altering the scope of the invention. Aluminum chloride will catalyze the addition of olefins to normal paraffins and naphthenes but as the reaction with isobutane is more rapid, by maintaining an excess of the latter, the character of the product can be readily controlled by the processes described hereinabove.

Further, it can be seen from the foregoing description that where it is desired to obtain a maximum degree of control on the character of the more volatile fractions in the finished alkylation product, unreactive hydrocarbons containing 5, 6 and even 7 carbon atoms can be included in either the reacting olefin or isoparaffin fraction or both.

Other features, advantages and objects of the present invention will become apparent to those skilled in the art from the following specific examples:

Example 1

By the stabilization of natural gasoline and pressure distillate, respectively, isobutane and olefin containing fractions of the following compositions were prepared:

	Isobutane fraction, per cent by vol.	Olefin fraction, per cent by vol.
Ethane		0.2
Ethylene		2.5
Propane	15.1	19.3
Propylene		6.9
Isobutane	77.9	19.4
n-Butane	7.0	22.8
Iso-n-butylens		22.8
Isopentane		3.7
Isopentenes		2.4
	100.0	100.0

Approximately 5.11 gallons per hour of the isobutane fraction and 1.25 gallons per hour of the olefin fraction were mixed with a recycled hydrocarbon stream, as indicated below, and subsequently intimately contacted with sulphuric acid or approximately 98% H_2SO_4 content. The reaction mixture was passed into a settling chamber and allowed to separate into two phases, an upper hydrocarbon phase and a lower acid phase. In order to maintain the desired ratio of reactive isoparaffins to olefins contacting the acid, a portion of the reaction product separated from the acid was recycled at a rate of approximately 11.0 gallons per minute and mixed with the olefin and isoparaffin fractions being introduced into the system as described above. The reaction was conducted at a temperature of approximately 55° F. and the reaction system was maintained under

sufficient pressure, approximately 90 pounds per square inch, to maintain the reactants in a liquid state. An amount of reaction product equivalent to the amount of olefin and isoparaffin fractions introduced into the system was continuously withdrawn and stabilized to remove materials boiling below isopentane.

The composition of the stabilized reaction product was as follows:

	Per cent by volume
Pentanes	21
Hexanes	8
Heptanes	16
Octanes	26
Nonanes	8
Decanes and higher	21

The stabilized material contained substantially no olefinic or aromatic hydrocarbons and had a knock-rating (as determined by the A. S. T. M. method) of 90.

Example 2

The procedure described in Example 1 was repeated using stocks which contained substantially no hydrocarbons boiling above normal butane. The resultant stabilized reaction product had the following composition:

	Per cent by volume
Pentanes	2
Hexanes	13
Heptanes	20
Octanes	27
Nonanes	5
Decanes and higher	33

The stabilized product contained substantially no olefinic or aromatic hydrocarbons and had a knock-rating of 89.

A comparison of the results of the two above described experiments discloses a considerably higher volatility for the product prepared from the fractions containing a mixture of both isobutane and isopentane and it will be noted that such increase in volatility was obtained without any loss in knock-rating.

The foregoing description of my invention is not to be construed as limiting but only as illustrative of the invention as many variations may be made within the scope of the following claims.

I claim:

1. A process for the production of isoparaffinic motor fuels of improved volatility and anti-detonation characteristics which comprises subjecting a hydrocarbon feed stock boiling completely below the boiling point of normal pentane and containing olefins, isobutane, and isopentane, to alkylation in the presence of an alkylation catalyst, and separating directly from the reaction product by distillation a fraction consisting of unreacted isopentane and products of the alkylation reaction boiling above normal butane and substantially free of normal pentane; the molal proportions of olefins, isobutane and isopentane in said hydrocarbon feed stock being such that the ratio of isobutane to isopentane is at least 1 to 1; and the ratio of isobutane plus isopentane to olefin is at least 3 to 1.

2. A process according to claim 1 in which the olefins consist of butenes.

3. A process according to claim 1 in which the alkylation catalyst is concentrated sulfuric acid.

4. A method of producing motor fuel which comprises reacting an isoparaffinic feed stock

boiling completely below the boiling point of normal pentene and containing isobutane and isopentane but no higher boiling material with an olefinic feed stock containing butylenes but no higher boiling material in the presence of an alkylation catalyst, and separating directly from the resulting mixture by distillation a fraction comprising alkylated hydrocarbons substantially free of normal pentane and containing a substantial proportion of unreacted isopentane; the molal proportions of isobutane, isopentane and butylenes in the reaction mixture being such that the ratio of isobutane to isopentane is at least 1 to 1, and the ratio of isobutane plus isopentane to butylene is at least 3 to 1.

5. In a process of producing a motor fuel by alkylating isobutane with an amylene lower boiling than normal pentane, wherein a hydrocar-

bon mixture containing said amylene, isopentane, normal pentane and another amylene higher boiling than normal pentane is used as the source of the said lower boiling amylene, the method of increasing the yield of desirable isobutane alkylation products and the quality of the hydrocarbon components of the reaction mixture boiling in the gasoline range which comprises distilling said hydrocarbon mixture to separate an isopentane-amylene fraction substantially free from said normal pentane and higher boiling amylene, reacting the separated fraction with isobutane in the presence of an alkylation catalyst under alkylation conditions and recovering a substantially isoparaffinic mixture containing iso-pentane and alkylation products of isobutane.

WILLIAM E. BRADLEY.
